UNITED STATES PATENT OFFICE.

WILLIAM BRANGHAM AND WILLIAM EDWIN HARRIS, OF NILES, OHIO.

DESIGN FOR A GREASE-POT FOR TINNING-MACHINES.

SPECIFICATION forming part of Design No. 24,743, dated October 8, 1895.

Application filed September 6, 1895. Serial No. 561,707. Term of patent 3½ years.

To all whom it may concern:

Be it known that we, WILLIAM BRANGHAM and WILLIAM EDWIN HARRIS, of Niles, in the county of Trumbull and State of Ohio, have 5 invented a certain new and original Design for Grease-Pots for Tinning-Machines; and we do hereby declare the following to be a full, clear, and exact description of the invention, such as will enable others skilled in the art to 10 which it appertains to make and use the same.

This is a design for grease-pots for tinning-machines.

In the accompanying drawings, Figure 1 is a view in perspective. Fig. 2 is a transverse 15 sectional view.

The leading or characteristic feature of our design is the open-top receptacle A, of rectangular form at its upper end and tapering inwardly at one side a and at its ends a', its

other side a² being perpendicular. The bottom a³ is extended laterally, forming flanges a³^x. The top or upper end of side a is extended outwardly at a⁴, overhanging or projecting beyond said side. One end a⁵ of said top has a ledge a⁶ projecting therefrom and formed with a series of holes or openings a⁷.

We claim as our invention—

The design for grease-pots for tinning machines, substantially as herein shown and described.

In testimony whereof we have signed this specification in the presence of two subscribing witnesses.

WILLIAM BRANGHAM.
WILLIAM EDWIN HARRIS.

Witnesses:
